STOKER TUYÈRE

Fred B. Hall, Worcester, Mass., assignor to Riley
Stoker Corporation, Worcester, Mass., a corpo-
ration of Massachusetts

Application December 12, 1942, Serial No. 468,860

6 Claims. (Cl. 110—44)

1

This invention relates to stoker tuyères, and more particularly to a tuyère construction for use with multiple retort underfeed stokers of the well known Riley type having reciprocable retort side walls.

When certain fuels are burned on stokers of this type there is a tendency for the combustion to be considerably more active directly above the tuyère rows than above the retorts, whereas a more uniform distribution of combustion activity is desirable in the interests of maximum capacity and efficiency. It has heretofore been proposed to remedy this difficulty by utilizing so-called "plate type" tuyère blocks, which comprises web portions provided with ribs on one or both sides to form tuyère openings, the individual blocks being mounted side by side in planes substantially perpendicular to the upper margins of the retort side walls and the arrangement being such that some of the jets of air are directed transversely of the retorts. As heretofore proposed such plate type tuyère constructions have failed to remain in proper position on the stoker, or have interfered with the relative reciprocating motion of adjacent retort side walls. In some cases the prior arrangements have been too expensive for practical use, and in other cases they have been subject to rapid destruction by the heat of the fuel bed.

It is accordingly one object of the invention to provide an improved plate tuyère construction particularly adapted for use with multiple retort underfeed stokers having reciprocable retort side walls.

It is a further object of the invention to provide a plate tuyère construction which can be held firmly in position on the retort side walls, and which will in no respect interfere with the reciprocation thereof.

It is a further object of the invention to provide a plate tuyère construction which will be comparatively simple and inexpensive to manufacture, and capable of operating efficiently throughout a long life of usefulness.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a longitudinal section through one retort of a multiple retort underfeed stoker, taken on the line 1—1 of Fig. 2;

2

Fig. 2 is a section on the line 2—2 of Fig. 1; Fig. 3 is a section on the line 3—3 of Fig. 2; Fig. 4 is a perspective view of one tuyère block; Fig. 5 is a fragmentary perspective view of a

slightly modified tuyère block; and

Fig. 6 is a perspective view of a bar forming a part of the tuyère construction.

In the drawings there is illustrated a multiple retort underfeed stoker of the well known Riley type comprising a series of parallel retorts 10 extending rearwardly from the front wall 11 of a furnace. Each retort is provided with a stationary bottom plate 12 and two horizontally reciprocable upright hollow side walls or side bars 14 which slope downwardly and rearwardly. The rear ends of the side bars are connected to shoes 15 which are slidably supported upon a stationary structure 16. The rear portions of the side bars carry overfeed grates 18. Any suitable and well known means may be provided for reciprocating the side bars of each retort relative to the side bars of adjacent retorts and for supplying fuel to the front ends of the retorts. The usual siftings strips 19 are attached to the sides of the retort bottoms 12 to engage the moving side bars and prevent leakage of the fuel. Air for combustion will be supplied under pressure to the space beneath the retorts in known manner, this air flowing upwardly through the hollow side bars 14.

The present invention provides an improved tuyère structure which is mounted on the retort side bars 14 to support the fuel bed thereabove and to distribute the combustion air. This structure includes a series of tuyère blocks 21 each comprising an upright web or plate 22 (Fig. 4) having spaced ribs 23 thereon extending generally horizontally to form channels for the discharge of air from the inner edge of the block into the retort. At the bottom of the inner edge of the block there is provided a downwardly projecting lug 24 which overlaps the inner surface of an upwardly projecting rib 25 (Fig. 2) on the upper edge of the side bar 14 to form a shiplap joint. This rib 25 is spaced outwardly from the inner surface of the side bar. The web 22 is provided adjacent its upper edge with spaced upright ribs 27 arranged to direct some of the air upwardly. Between the horizontal ribs 23 and the upright ribs 27, adjacent the nose or upper inner portion of the block, there is provided a triangular rib or boss 29 which preferably projects from the web a less distance than the ribs 23 and 27. This construction serves to discharge air not only at 50 both sides of the boss 29 but also across the face

of this boss, thus effectively cooling the nose portion of the block and enabling it to withstand the severe heat conditions to which it is subjected in service. In order that the block may remain in use even after the nose portion thereof has been burned away, an angularly positioned rib 31 is provided adjacent the corner of the boss 29 remote from the nose of the block. Preferably both sides of the web 22 are provided with the same arrangement of ribs 23, 27, 29, and 31.

Means is provided to hold the tuyère blocks 21 in the proper assembled relationship. For this purpose there are provided bars 33 each having two ribs 34 extending along its upper and lower edges respectively, and a rib 36 extending along its inner face. Each tuyère block is provided at its outer edge with a pair of opposed hooks 37 one of which is located directly beneath the other. The upper hook is positioned adjacent the top of the block and projects downwardly, whereas the lower hook projects upwardly. At assembly these hooks embracingly engage the ribs 34, the rear edge of the web 22 engaging the rib 36. Each of the bars 33 is long enough to connect with several of the tuyère blocks. The outer faces of the bars in adjacent rows are in rubbing contact, as indicated in Fig. 2, thus preventing any contact or interference between the tuyère blocks 21 in adjacent rows. In order to prevent any possibility of interference between the bars 33 in adjacent rows, the end portions of their outer surfaces are beveled as indicated at 39 in Fig. 6.

In order to hold the tuyère blocks in place on the side bars 14, a downwardly extending tail 41 may be provided on the web 22 to project downwardly into the side bar. Each of these tails 41 has an opening 42 therethrough for the reception of a rod 43 which is connected by a hook bolt 45 to the bottom of the side bar. Each of the rods 43 may extend through several of the tails 41, as shown in Fig. 3, but it is not necessary that all the tails be engaged by the rods, since the bars 33 serve as connecting devices for adjacent tuyère blocks. Furthermore, the tails may be omitted entirely from certain of the blocks in order to avoid interference with transverse strengthening ribs 48 in the side bars 14.

In some cases it may be desirable to provide upward extensions 50 on the webs 22 of certain of the tuyère blocks, in order to obtain a more positive rearward feeding of the fuel. These extensions 50 form shoulders which will enable the moving rows of tuyère blocks to push the fuel more effectively during their rearward travel. Because of the rearward inclination of the side bars, there will be substantially no tendency to drag the fuel forwardly on the idle stroke.

The operation of the invention will now be apparent from the above disclosure. Fuel is delivered into the front ends of the retorts 10 by the usual feeding devices. The reciprocating movements of the retort sides and tuyère blocks carry the fuel slowly to the rear, while air flows past the tuyères to support the combustion. The ribs 23 direct a considerable portion of the air laterally into the retorts and thus tend to maintain a more uniform rate of combustion across the stoker. The shallow triangular ribs 29 allow air to flow past the nose portions of the blocks in substantial amounts to prolong the life of these relatively exposed corners, and if they should burn away after long service the ribs 31 will still remain to prevent excessive sifting of the fuel and to permit continued operation of the tuyère blocks. The bars 33 not only hold the tuyère blocks in

correctly assembled relationship but they also provide smooth surfaces of large area for rubbing contact with the laterally adjacent bars, thus forming an effective seal between the sides of adjacent retorts. The assembled tuyère blocks are firmly held against the side bars by means of the rods 43 and the hook bolts 45. The lugs 24 and rib 25 provide a shiplap joint which forms an effective air seal to prevent combustion from taking place too low in the retort. The construction is comparatively simple and inexpensive to manufacture and install.

Having thus described my invention, what I claim as new and desire to secure by Letters Patent is:

1. A tuyère block for an underfeed stoker comprising an upright web, a series of spaced ribs on the web extending generally horizontally to form channels for the discharge of air from the inner edge of the block, spaced upright ribs on the web adjacent its upper edge, a triangular boss on the web adjacent its upper inner portion or nose, and an angularly positioned rib on the web adjacent the corner of the boss remote from the nose.

2. A tuyère block for an underfeed stoker comprising an upright web, a series of spaced ribs on the web extending generally horizontally to form channels for the discharge of air from the inner edge of the block, spaced upright ribs on the web adjacent its upper edge, a triangular boss on the web adjacent its upper inner portion or nose and projecting from the web a less distance than the horizontal and upright ribs, and an angularly positioned rib on the web adjacent the corner of the boss remote from the nose.

3. An underfeed stoker comprising a retort side wall having an upwardly projecting rib extending along the upper edge thereof and spaced outwardly from the inner surface of the side wall, and a series of tuyère blocks mounted on the upper edge of the side wall, each block including an upright web, a series of spaced ribs on the web extending generally horizontally to form channels for the discharge of air from the inner edge of the block, and a lug projecting downwardly from the inner edge of the block in overlapping relation with the inner surface of the rib on the retort side wall, the lug extending along the said rib throughout the entire width of the block.

4. An underfeed stoker comprising two adjacent retort side walls arranged for relative reciprocation, a row of tuyère blocks mounted on the upper edge of each side wall, each tuyère block having an upright web, spaced ribs on the web to form channels for the discharge of air from the inner edge of the block, a downwardly projecting hook at the outer edge of the web and adjacent the top of the block, and an upwardly projecting hook at the outer edge of the web and directly beneath the first-mentioned hook, and a bar extending past the outer edges of the blocks in each row and embracingly engaged by the hooks to hold the blocks in assembled relation, the bars for adjacent rows being in rubbing contact with each other.

5. A tuyère structure for an underfeed stoker comprising a series of juxtaposed tuyère blocks each including an upright web having spaced air-distributing ribs adjacent its inner edge, a downwardly projecting hook at the outer edge of the web and adjacent the top of the block, and an upwardly projecting hook at the outer edge of the web and directly beneath the first-mentioned

hook, and a bar extending past the outer edges of the webs and embracingly engaged by the hooks to hold the blocks in assembled relation.

6. A tuyère structure for an underfeed stoker comprising a series of juxtaposed tuyère blocks each including an upright web having spaced air-distributing ribs adjacent its inner edge, a downwardly projecting hook at the outer edge of the web and adjacent the top of the block, and an upwardly projecting hook at the outer edge of the web and directly beneath the first-mentioned hook, and a bar extending past the hooks, the bar having a rib on its inner surface for engagement with the outer edges of the webs and ribs on its top and bottom surfaces which are embracingly engaged by the upper and lower hooks respectively to hold the blocks in assembled relation.
